UNITED STATES PATENT OFFICE

168,366

DISPLAY RACK OR SIMILAR ARTICLE

Milton C. Miner, Freeport, Mich.

Application May 9, 1952, Serial No. 19,641

Term of patent 7 years

(Cl. D80—9)

To all whom it may concern:

Be it known that I, Milton C. Miner, a citizen of the United States of America, residing at Freeport, in the county of Barry and State of Michigan, have invented a new, original, and ornamental Design for a Display Rack or Similar Article, of which the following is a specification, reference being had to the accompanying drawing, forming part thereof.

Fig. 1 is a perspective view of the display rack of my design.

Fig. 2 is an end elevation thereof.

The back of the rack is plain in appearance.
I claim:

The ornamental design for a display rack or similar article, substantially as shown and described.

MILTON C. MINER.
